UNITED STATES PATENT OFFICE.

ALFRED BONOM, OF PATERSON, NEW JERSEY.

TURBINE.

1,027,309.

Specification of Letters Patent.

Patented May 21, 1912.

Application filed March 2, 1911. Serial No. 611,784.

To all whom it may concern:

Be it known that I, ALFRED BONOM, a citizen of France, residing at Paterson, in the county of Passaic and State of New Jersey, have invented certain new and useful Improvements in Turbines, of which the following is a specification.

My invention relates to improvements in turbines, and in particular to a turbine 10 blade and the means by which the blades are secured in place.

The general object of my invention is to provide a construction whereby the blade will be readily manufactured to the proper 15 shape and at the same time when in place will be rigidly held against centrifugal force.

With these general objects in view and some others which will be obvious to those skilled in the art from the description hereinafter, my invention consists in the features, details of construction and combination of parts which will first be described in connection with the accompanying drawings and then particularly pointed out in 25 the claims.

In the drawings,—Figure 1 is a longitudinal section partly broken away of parts of a rotor and stator embodying my invention; Fig. 2 is a transverse section of the 30 structure shown in Fig. 1; Fig. 3 is a perspective view of one of the blades, and Fig. 4 a side elevation of the same. Fig. 5 is a detail view of another form of blade embodying my invention.

Referring to the drawings, A indicates the stator of a turbine, and B the rotor, only so much of each being shown as is necessary for an understanding of my invention. The stator is provided with a plurality 35 of sets of stator blades, indicated at C and the rotor is provided with a plurality of sets of rotor blades, indicated at C¹, the sets of rotor blades alternating with the sets of stator blades in the usual way. Each 40 blade, as is shown in Figs. 3 and 4 consists of a vane portion, indicated at c, this vane portion being concave on one side and convex on the other side, the respective curvatures being such as are suitable for the 45 proper economical operation of the engine. Each blade also has two end flanges, one, indicated at c¹, being of the full width of the blade and having its outer free edge c² curved so as to be parallel to the curve of 50 the concave surface of the vane portion. By this arrangement the said free edge c² of one blade will fit accurately against the concave surface of the adjacent blade of the set. The other end flange c³ of each blade also has its outer free edge curved to fit the 55 concave portion of the adjacent blade of the set, but is narrower than the vane portion of the blade and has its lateral edges c⁴ beveled outward. This flange c³ serves to attach the blade in place in the rotor or 60 stator, respectively, and may be termed the securing flange, while the other end flange c¹ may be termed the face or front flange.

The rotor is provided with a plurality of dovetailed annular grooves, each groove 65 serving to receive the securing flanges of one set of rotor blades, which thus form a ring of blades, fitting closely together, the beveled securing flanges of a set fitting tightly into the dovetailed groove for such set. In 70 order to permit the ready insertion and removal of the blades, a radial groove is formed, as indicated at E, this groove being arranged to be closed by suitable filling pieces F which are suitably secured in place 75 as by countersunk machine screws. The rotor blades are inserted in their respective annular grooves by first inserting the securing flange in the radial groove, E, then sliding the blade down said groove until it 80 alines with the respective annular groove, and finally sliding it around in the said annular groove until it is brought to its proper position. When all the blades of a set have 85 been inserted in a groove, they interlock to 90 form a ring of blades, in which the convex edges of the flanges fit tightly against the ends of the concave vane portions of the adjacent blades in the set, so as to mutually support one another against outward stresses 95 due to centrifugal force. The face flanges of a set of rotor blades travel in an annular groove formed in the stator, as indicated at G, such annular groove being of a depth about equal to the thickness of the face 100 flanges, only sufficient clearance being provided to avoid unnecessary friction. The stator blades are secured in place in the stator in the same way that the rotor blades are secured in the rotor, and the face flanges 105 of the stator blades are received in annular grooves in the rotor. As the steam passes radially outward or inward it impinges alternately against the curved surfaces of the vane portions of the rotor and stator blades, 110 in the usual manner whereby the rotor is rotated.

The advantages of my construction are that the form of the blades is such as to permit of rapid and economical manufacture since the concave surface, which must have 5 the proper curvature, is not interrupted by any projections and hence may be readily grooved or otherwise worked to the desired curvature by simple apparatus. That is to say the butting curvature of a blade is identical with the active steam jet curvature of 10 the blade, so that in manufacture each blade may be passed over a machine tool and a polisher, thus insuring the correct form of jet curvature, which is impossible when the 15 flanges project beyond the jet surface, as in prior constructions. Also, the nesting or interlocking of the blades of a set with each other to form a ring provides a strong construction, since the centrifugal force acting 20 on one blade is transmitted to the neighboring blades on both sides, the assembled circle or ring of blades forming a very compact unit as if cast in one piece.

Having thus fully described my invention, 25 what I claim is:

1. In a turbine, the combination, with a rotor provided with an annular dovetailed groove, a radial groove extending therefrom and means for filling said radial groove, of 30 a blade having an uninterrupted curved jet surface and provided on its opposite side

with end flanges having their edges curved to fit the curvature of the jet surface of the next blade in the set, one of said end flanges being beveled to fit in the dovetailed annular 35 groove of the rotor.

2. In a turbine, the combination, with a rotor, of a blade having an uninterrupted curved jet surface and provided on its opposite side with end flanges having their 40 edges curved to fit the curvature of the jet surface of the next blade in the set, and means for securing said blade to the rotor.

3. In a turbine, the combination, with sets of rotor and stator blades, each set forming 45 a ring, each blade having an uninterrupted curved jet surface and being provided on its opposite side with end flanges having their edges curved to fit the curvature of the next blade of the set, of a rotor to which the rotor 50 blades are secured, said rotor having annular grooves to receive the end flanges of the stator blades, and a stator to which the stator blades are secured, said stator having annular grooves to receive the end flanges 55 of the rotor blades.

In testimony whereof, I affix my signature in the presence of witnesses.

ALFRED BONOM.
